UNITED STATES PATENT OFFICE

162,594

WARDROBE CABINET

Daniel Tames, Chicago, Ill.

Application May 10, 1950, Serial No. 9,843

Term of patent 14 years

(Cl. D33—19)

To all whom it may concern:

Be it known that I, Daniel Tames, a citizen of the United States of America and a resident of the city of Chicago, in the county of Cook and State of Illinois, have invented a new, original, and ornamental Design for a Wardrobe Cabinet, of which the following is a specification, reference being had to the accompanying drawing, forming a part thereof.

Fig. 1 is a front view of a wardrobe cabinet showing my new design;

Fig. 2 is a front view thereof with the doors in open position and the drawers and slides in pulled-out position;

Fig. 3 is the left side view thereof with the door in open position and the front drawer and slides in pulled-out position; and

Fig. 4 is a right side view thereof with the door in open position.

I claim:

The ornamental design for a wardrobe cabinet, substantially as shown.

DANIEL TAMES.
